RAYMOND D. SMITH, OF BOSTON, MASSACHUSETTS, ASSIGNOR TO SHAWMUT MACHINE WORKS, INC., A CORPORATION OF MAINE.

DELAYED CUT-OFF ARRANGEMENT FOR MANTLE GAS LAMPS.

1,415,063.

Specification of Letters Patent.

Patented May 9, 1922.

Application filed August 7, 1916, Serial No. 113,547. Renewed September 30, 1921. Serial No. 504,493.

To all whom it may concern:

Be it known that I, RAYMOND D. SMITH, a citizen of the United States, residing at Boston, in the county of Suffolk and State 5 of Massachusetts, have invented certain new and useful Improvements in Delayed Cut-Off Arrangements for Mantle Gas Lamps, of which the following is a specification.

My present invention relates to details of 10 construction and arrangement that have been found advantageous in applying an improved form of thermostatic valve control to a mantle gas lamp structure, specifically of a well known commercial type wherein the 15 lighting unit thereof comprises a fixedly-assembled cage structure that includes an upright mica chimney permanently secured to a metallic base and carrying across its top a wire or other means of support for an illuminating mantle centrally suspended therein.

Such type of gas lamp structure, which in one of its commercial forms is known in this 20 country as the "Welsbach Junior Light," is characterized by comparatively diminutive size and commonly employs an outer light-diffusing globe that to well serve its 25 designed purpose is spherical in form, and small, yet considerably larger than the above 30 described illuminating unit which it surrounds and that, therefore, extends considerably below the base of such unit thereat to be supported upon a suitable holding bracket.

The form of thermostatic valve control 35 which I apply to such type of gas lamp, however, embodies the provision of a small, auxiliary Bunsen-burner preferably positioned laterally of the stem of the mantle 40 burner and preferably just below the mantle-containing illuminating unit, which auxiliary burner is thus of necessity brought into juxtaposition to the above described conventional outer globe if the desirable compactness characterizing the type of lamp 45 concerned is to be retained.

The principal object of this invention is 50 to incorporate in self-contained form with a mantle gas lamp of the type above described, including the fuel control valve therefor, an apparatus embodying mechanism for effecting direct hand actuation of the valve as usual and also including thermostatically controlled devices for effecting an automatically delayed extinguishment of the illumina-

nating burner upon manipulation of the control means such as customarily turns out the gas. Apparatus of this kind is shown, as applied to a different form of burner, in my copending application, Serial No. 111,934,— 60 the auxiliary burner herein employed for heating the thermostat being automatically ignitable, as in the above mentioned application, from the heat of the mantle burner.

In accomplishing this object, I have de- 65 vised a simple and effective expedient to care for certain new conditions and problems arising in the application of this form of thermostatic valve control to the type of burner hereinbefore described; such expe- 70 dient, however, being useful in other connections than in the precise application thereof made in this disclosure. The expedient referred to consists in the provision of a shield for the flame of the auxiliary burner 75 arranged, at once, to insure the automatic ignition of the latter, to protect the hereinbefore mentioned closely adjacent outer globe from the heat of such burner, and to shield the flame thereof from outside drafts or 80 other disturbance after the burner has been ignited.

Other details and specific objects of my 85 invention will appear from the drawings, description and claim hereof.

In the drawings:—Fig. 1 is a plan view of the burner structure taken in section on the horizontal plane 1—1 in Fig. 4, the outer shade being omitted; Fig. 2 is a front elevation of the valve mechanism and certain aux- 90 illiary burner parts, the mechanical parts being shown in their positions after manual operation of the extinguishing means and before automatic closure of the valve or while the thermostat is being heated; Fig. 3 is a 95 view similar to Fig. 2, showing the position of parts after automatic closure of the valve; Fig. 4 is a rear elevation partly in section of the entire burner and valve structure including the outer shade; Fig. 5 is an en- 100 larged partial section taken on the plane 4—4 in Fig. 8, showing the arrangement of valve ports and their relative positions during normal operation of the main illuminating burner; Fig. 6 is a section similar to 105 Fig. 4, showing a different relation of ports; Fig. 7 shows the relation of ports when the light has been extinguished; Fig. 8 is a plan view of the valve, and actuating mechanism therefor, with casing and thermostat broken 110

away; Fig. 9 is an elevation looking at the right of Fig. 4 the outer shade being omitted and the shade holder shown in section.

Similar and corresponding parts are indicated throughout the drawings and designated in the following description by the same numerals.

Referring to Fig. 7, particularly, the illuminating mantle appears at 1 and is of the conventional type suspended by its top from a wire support 2, diametrically bridging the open top of a self-contained chimney and supporting bracket structure 3, which has transparent mica walls with the usual openings 4 therein and which is substantially closed at the bottom with the exception of the necessary fuel opening beneath the mantle, and one other opening to be referred to herein-after.

This self-contained mantle and chimney structure 3 is adapted to be mounted on the open and enlarged upper portion of the upright, combined supporting stem and mixing chamber 5 for the gas and air of the main Bunsen burner. At the bottom of the mixing chamber 5, is shown the usual gas injector and air intake construction, wherein adjustment of the gas supply may be had by means of the knurled needle-valve screw-cap 6, which latter has a central tapered orifice for the gas adapted to seat over the upwardly and conically pointed, stationary projection 7, and wherein air is admitted through the openings 8 in the wall of the mixing chamber, such openings being partially covered by the circular hood 9, this type of Bunsen gas burner construction being well known in the art.

The combined supporting stem and mixing chamber 5 terminates below the Bunsen gas injector construction in an internally threaded portion 11 and is mounted at this portion upon a valve block 12, which latter at its bottom, has an internally threaded portion 14 by means of which the entire structure may be mounted upon the usual gas bracket or chandelier.

Clamped between the stem 5 and the valve block 12 is the base of a three armed bracket or shade holder 13. A spring clamp wire 17 holds the shade 16 firmly seated on the bracket 13.

The valve block 12 contains the usual tapered valve plug 15 whose axis lies transverse of the vertical main gas passage 18 through said block, and which, when rotatively actuated by mechanism to be described hereinafter, controls the supply of gas to both the main burner stem 5 and to a small auxiliary heater burner 21 extending upwardly from a bracket extension 22, of the valve block.

It should be carefully noted that the upper orifice of the auxiliary heater burner 21 is at a substantially higher level than the

open, bottom portion of the air intake opening hood 9, and that said hood effectively separates the air intake openings from the burner 21.

Were such openings not thus shielded from the flame of the auxiliary burner, the latter would ignite the gas at its point of injection into the main burner mixing chamber and thereby impair the operation of the main illuminating burner.

I have provided and mounted only for convenience on the top, or mouth, of burner 21 the curved flame shield 40. The phenomena of back-firing gas ignition, i. e.—the igniting of a relatively low-positioned burner by means of conducting the gas issuing therefrom to a relatively highly positioned source of heat—is governed by certain well defined principles. It is hereinafter explained that the burner 21 is adapted to be supplied with gas only at certain times and at such times to be automatically ignited by the rising of such gas to the heat of the illuminating mantle 1. It is, therefore, such back-firing principle of ignition that is depended upon in the working of the present device. Experience shows, however, that a too closely confining conduit for leading the unburned gas to its source of ignition excludes the presence of air and, therefore, of oxygen and defeats the reliable ignition desired. Also one cannot depend on gas rising directly vertically, when entirely undirected, because drafts and air currents tend to waft the gas away from its true vertical course. The solution, therefore, must be a compromise, or partially encompassing gas directive-means, and such constitutes the simple form of flame shield 40. This shield while partially constraining the rising gas to its vertical path allows it free intercourse with the atmosphere and while thus acting to insure the reliable ignition of the auxiliary burner, also protects the outer shade or globe 16, which latter, if retained in its conventional and desirable form and position, must fall closely adjacent to the flame of the auxiliary burner, as before explained. Adjustment of the supply of gas to the burner 21 may be had by the screw 23.

In the other extension 24 of the valve block 12, an upwardly slanting gas port 27 is shown leading from the main gas passage, below the valve plug 15, to the base of a small upright tube 25. This tube enters the enlarged upper portion of the main burner chamber and its top orifice lies centrally within the lower portion of the mantle. Gas supply to this tube may be controlled by the adjusting screw 26. When ignited it will be evident that the small flame 29 at the top of the tube, commonly called a pilot light, will remain constantly burning independent of the valve plug 15 and that this flame is so situated as to ignite the main

mantle burner whenever gas is supplied to the latter.

Referring particularly to Figs. 2, 3 and 8, I shall now describe the mechanism by which the movement of the valve plug 15 is controlled. Manual control of the mechanism is afforded by the chains 65 and 68. A downward pull on chain 68 in Fig. 3 first swings the spring actuated latch lever 66 to the broken line position, thus disengaging it from the locking projection 78 of the supporting plate 31, which plate is fixed to the valve block 12. The latch lever 66 is pivoted to one end of the double-ended control lever 35, which latter is loosely and pivotally mounted on a stem extension 30 of the valve plug 15 and which carries at its opposite end the chain 65. Further pull on the chain 68 will therefore swing the control lever 35 to its position indicated by broken lines in Fig. 3, where it will be stopped by engagement with another projection 54 of the supporting plate 31. During this movement, the valve plug has been positively rotated a corresponding amount by engagement of the control lever 35 with a rearwardly bent extension 37 of the dog member 36 the latter being fast to the end of the valve stem 30 and normally maintained in such engagement with the control lever 35 by a spring 38; one end of which is hooked under the edge of control lever 35 and the other end of which is hooked over the extension 37.

Control chain 65 may now be pulled downwardly which will swing the control lever 35 in the reverse direction until the spring latch lever 66 automatically locks it in the position shown in Figs. 2 and 3. But from Fig. 2 it will be seen that during this latter movement, the dog member 36 has been intercepted in an intermediate position and that it is held in this position against the tension of spring 38 by a spur shaped projection 52 carried fast to the inner surface of the curved, bi-metallic thermostat 53.

The thermostat 53 is mounted at one end to the projection 54 of the supporting plate 31 and is clamped thereto in contact with the base of an upwardly extending, heater member 56, by screws 55, 55. The heater member 56 terminates in a hooded portion 57 that is perforated at its top and is positioned directly over the auxiliary burner 21. This hooded terminal of the heater member lies directly beneath an opening 41 in the base of the main burner chimney structure 8, said opening having downwardly flanged edges to better collect the gas arising from the auxiliary burner 21 and through the opening in the top of the heater hood. Such gas upon rising and entering the mantle chamber ignites from the heat of the main mantle burner and flares back through said opening subsequently burning with a hot, blue, concentrated flame at the top of the aux-

iliary burner only and under the hood 57 as shown in Fig. 2. A loose stationary roller 61 is mounted on a stud projecting from the support plate 31 and engages the inner surface of the thermostat to help the thermostat bear the load of the tensioned dog member 36. This dog member engages the thermostat spur 52 by means of a spring actuated latch 46 pivoted to the dog member at 47 and capable of yielding in one direction 75 only, namely counter-clockwise in Fig. 2, or when passing the spur 52 by clockwise rotation of the dog member 36.

Having thus described the controlling mechanism I shall now explain the operation of the complete burner and valve arrangement after which I shall point out what constitutes the novel features of my invention in the appended claim.

Starting from the position of parts as shown by broken lines in Fig. 3, where the valve ports are related as in Fig. 5 and where the main mantle burner is lighted and adapted for continuous operation, when it be desired to extinguish the light, 85 control chain 65 is pulled downwardly, which moves the parts to the position indicated in Fig. 2, where the valve ports are related as shown in Fig. 6. Here it will be seen that the small port 19 in the valve 95 plug now registers with the corresponding port 20 leading to the auxiliary burner which then ignites from the heat of the mantle burner as heretofore described, the supply of gas to which latter burner has 100 been substantially unaltered by the movement of the valve plug. The flame of the auxiliary burner now plays against the terminal 57 of the heater member 56 as shown in Fig. 2, which latter member conducts 105 heat from said flame to the thermostat. The thermostat, upon being heated, straightens or bends generally outwardly, assuming the broken line position indicated in Fig. 2 after a certain time interval, whereupon the spur 52 releases the dog member 36, and the latter is immediately impelled by the spring 38 to the position shown in Fig. 3, where the relation of the valve ports is as shown in Fig. 7, and all gas supply to 115 both the auxiliary heater burner and to the main mantle burner has been cut-off. The pilot flame 29 however remains burning and when gas is again supplied to the main mantle burner, ignites the latter.

The valve may be opened again at will for supplying gas to the main burner, by pulling downwardly on chain 68. This restores the valve plug to the position shown in Fig. 5 as before explained. It should 125 be noted that in this position, no gas is supplied to the auxiliary burner 21 and that the main mantle burner is adapted to remain in operation for an indefinite period of time.

Having thus described the construction and operation of a preferred embodiment of my present invention, what I claim as new is:

- 5 In a thermostatically-governable apparatus employing a gas burner for heating the thermostat thereof, in combination with said burner and a superposed source of ignition therefor; a heat-conductive member extending from said thermostat to a point above the mouth of said burner and thereat formed to permit gas issuing from said mouth to rise past said member toward the
- 10

said source of ignition; and a shield for the flame of said burner formed and positioned only partially to surround the space between the burner mouth and said member, so that the rise of said gas to its source of ignition may be insured substantially in the presence of free air.

Signed in Boston, Massachusetts, this 5th day of August, 1916.

RAYMOND D. SMITH.
